His Attorney.

UNITED STATES PATENT OFFICE

2,471,178

AIR CLEANING AXIAL FLOW BLOWER

Robert Walsh, Wilmington, Del., assignor to General Electric Company, a corporation of New York

Application September 3, 1947, Serial No. 771,955

5 Claims. (Cl. 183—37)

1

My invention relates to improvements in axial flow blowers, and more particularly to blowers of this type incorporating improved means for the removal of dirt and foreign particles from the air.

In many fields the need for an adequate supply of clean air, free from dirt or other foreign particles, is of paramount importance to the effective operation of certain apparatus. This is particularly true in the railway field with special emphasis on the supply of ventilating air to the electric driving motors for supplying tractive effort to railway locomotives. Due to their inherently small physical size and relatively large electrical rating, such motors require a large volume of cooling air in order to prevent overheating during continued periods of operation. Also, due to their physical location, being mounted either on or near the driving truck, they are in a position where large quantities of dirt and dust, agitated from the roadbed, may enter through the air circulating means.

It is, therefore, especially important that the motors designed for mounting on railway equipment and also on other equipment, which must operate under conditions where a large amount of foreign matter or dirt is present in the air, be provided with suitable air circulating means, such as fans, or blowers, in which provision is made for efficient removal of all, or substantially all, of the dirt and foreign matter from the cooling air before it is supplied to the electrical machinery.

It is, therefore, an object of my invention to provide an improved air cleaning type of axial flow blower.

It is another object of my invention to provide an improved form of axial flow fan that is simple, compact and effective in removing dirt and foreign particles from the air stream.

In accordance with a preferred form of my invention, I provide an axial-flow type of electric motor driven blower which is compactly built and designed for mounting in restricted space such as beneath the underframe of a locomotive. The air enters the blower radially and is deflected around a ninety degree bend, thereby separating the entrapped foreign material from the main body of the air stream by centrifugal action. The fan construction of the blower is provided with dual concentric sets of blades which are in axial alignment with the divided air stream, the inner set of blades acting as scavenging blades and providing only enough suction to insure that the dirt-laden air is propelled through the casing to a discharge. The outer set of concentric blades

2

are in axial alignment with the main air stream, and supply the required pressure to force the clean air to the railway traction motors, or to any other use in which a pressurized supply of clean air is required.

For a better understanding of my invention, reference should now be had to the accompanying drawing in which Fig. 1 shows schematically in cross section a view of my improved air cleaning axial flow blower; Fig. 2 is a radial cross sectional view taken along the line 2—2 of Fig. 1 showing the pitch of the inner scavenging blades, and Fig. 3 is also a radial sectional view, taken along the line 3—3 of Fig. 1, showing the pitch of typical outer axial flow fan blades.

Referring to the drawing, I have shown the horizontal plate or supporting member 1 upon which the device is mounted and which may be the underside of a locomotive cab or main frame. Secured to the plate 1 is a vertically mounted electric motor 2 carrying on the lower end of its rotor shaft the spider 3 which supports two sets of fan blades. The fan spider 3 is provided with an inner rim 4, an intermediate rim 5, and an outer peripheral rim 6. Surrounding the motor drive unit 2 is a cylindrical enclosure 7 for preventing dirt and foreign material from entering the enclosed motor space. The total unit including the motor 2, spider 3 and air cleaning apparatus is surrounded by an enclosure 8 which, as shown in Fig. 1, is provided with an annular opening 9 around the upper portion through which the dirt laden air enters. The clean air is discharged under pressure at the lower end of the casing 10 from whence it may be supplied to the encased electric drive motors of the locomotive, or any other apparatus requiring cleaned air. Positioned concentrically with the inner casing 7 and entirely surrounding this casing is the intermediate casing 11 which defines an annular space and, as shown, is also open at the upper end 12 forming an inlet for the dirt laden air. The lower end of the annular space between the casings 7 and 11 is connected to the discharge pipe 13 which opens to the atmosphere and through which the dirt laden air is removed from the apparatus for disposal in any convenient manner.

From the drawing, Fig. 1, it will be noted that the inner rim 4 of the motor spider is axially aligned with the inner casing 7 and the intermediate rim 5 is axially aligned with the intermediate casing 11, thereby defining a continuous annular chamber surrounding the motor space 55 exhausting to the outlet 13. The outer rim 6 of

the spider 3 is arranged to rotate immediately adjacent the inner wall of the outer casing 8, and it should be pointed out here that in order for most efficient operation of the device, the clearances between the inner rim 4, the intermediate rim 5 and the outer rim 6 with their respective casings should be kept as close as mechanically practicable.

The main impeller axial flow blades 14, which are mounted between the intermediate rim 5 and the outer rim 6, may be designed to move the cleaned air with any desired velocity depending on the blower characteristics required, and as shown in Fig. 3, for example, may be constructed with relatively large pitch so that considerable pressure may be created at the blower outlet 10 with a corresponding relatively high value of suction at the inlet 9. The high entering air speed at the inlet 9 is utilized in my invention to separate the dirt and foreign matter carried by the incoming air by centrifugal means at the inlet 9. In Fig. 1 it will be noted that the inlet 9 is positioned so that as the air enters at relatively high speed, it must traverse a ninety degree or greater bend before passing through the outer annular chamber and through the main impeller blades 14. This centrifugal action will force the entrapped foreign material and dirt to the outermost portion of the curving air stream, where it will be carried into the inner annular chamber formed between the casings 7 and 11. In order to maintain air flow moving through this annular chamber at a sufficient rate, a second set of impeller blades 15 are disposed between the inner rim 4 and intermediate rim 5. These blades may be of the scavenging type and, as shown in Fig. 2, for example, are constructed with relatively less pitch than the main impeller axial flow blades, the only purpose of the scavenging blades 15 being to move the dirt laden air through the annular chamber surrounding the casing 7 and to the outlet member 13, this air being exhausted directly to atmospheric pressure.

It should be understood that pitch of the blower blades 15 and 14, as shown in Figs. 2 and 3, is simply illustrative and should be selected by the designer, depending on the overall design of the blower, and the pressure and quantity of air required for the particular application at hand.

The motor spider may be easily assembled, for instance, by casting the rims 4, 5 and 6, and the impeller blades 14 and scavenging blades 15 integrally, since the impeller blades themselves do not require any close mechanical tolerances. It is, therefore, necessary only to carefully machine the edges of the rims 4, 5 and 6 so that close tolerance will be maintained between the rims and their respective axially aligned casings.

In operation, it will be found that the air cleaning action of the device is very efficient, substantially all of the entrapped foreign material being removed from the main air stream supplied at the blower outlet 10. In addition, the device is simple and compact and easily adapted for mounting in a restricted area. There are substantially no parts requiring maintenance except to ascertain that the rotating spider 3 and associated impeller blades are maintained in close alignment with the casings 7, 8 and 11.

While I have shown and described my invention as applied to a particular system and as embodying various devices diagrammatically shown, it will be obvious to those skilled in the art that changes and modifications may be made

without departing from my invention, and I, therefore, aim in the appended claims to cover all such changes and modifications as fall within the true spirit and scope of my invention.

What I claim as new and desire to secure by Letters Patent of the United States is:

1. A gaseous fluid circulating and cleaning device comprising a cylindrical casing having an annular inlet chamber in which a particle-laden fluid stream to be cleaned is adapted to be directed, means in said casing for separating from said fluid stream a portion of said stream with substantially all of said particles entrapped therein, an annular discharge passage for said particles and portion of said stream, a coaxial annular cleaned fluid discharge passage and gaseous fluid impelling means comprising a radially inner and a radially outer set of radial blades concentrically arranged, with each of said sets disposed in operative relationship with a different one of said discharge passages and thereby adapted to propel the respective portion of said stream axially therethrough.

2. A gaseous fluid circulating and cleaning device comprising a casing having an annular inlet chamber in which a particle-laden fluid stream to be cleaned is directed, means in said casing for separating from said fluid stream a portion of said stream with substantially all of said particles entrapped therein, a discharge passage for said particles and portion of said stream centrally positioned in said casing, a cleaned fluid stream outlet passage concentric with said discharge passage, and a gaseous fluid impeller disposed in operative relationship with said discharge passage and said outlet passage and arranged to be driven by a source of power, said impeller comprising an inner and an outer set of radial blades concentrically arranged and positioned so that said inner set lies in operative relationship with said discharge passage and said outer set cooperates with said outlet passage.

3. A gaseous fluid circulating and cleaning device comprising a casing having an annular inlet chamber in which a particle-laden fluid stream to be cleaned is directed, means in said casing for directing said fluid stream through approximately a 90° bend for separating from said fluid stream a portion of said stream with substantially all of said particles entrapped therein, a discharge passage for said particles and portion of said stream centrally positioned in said casing, a cleaned fluid stream outlet passage concentric with and surrounding said discharge passage, and a gaseous fluid rotary impeller disposed in operative relationship with said discharge passage and said outlet passage and arranged to be driven by a source of power, said impeller comprising an inner and an outer set of radial blades concentrically arranged and positioned so that said inner set lies in operating relationship with said discharge passage and said outer set cooperates with said outlet passage.

4. An axial flow gas cleaner and blower comprising an outer cylindrical casing having a peripheral gas inlet adjacent one end thereof, an inner casing concentric with said outer casing, an intermediate casing between said inner and outer casings and concentric therewith, a driving motor within said inner casing and axially aligned therewith, a rotary gas impeller secured for operation to said driving motor, said impeller consisting of an inner set of radial blades having their inlet side in alignment with the space between said inner casing and said intermediate

casing, and an outer set of radial blades having their inlet side in alignment with the space between said intermediate casing and said outer casing, and duct means adjacent the discharge side of said inner and outer sets of blades for maintaining separate the gas flow through said inner and outer sets of impeller blades.

5. An axial flow gas cleaner and blower comprising an outer cylindrical casing having a peripheral gas inlet adjacent one end thereof, an inner casing concentric with said outer casing, an intermediate casing between said inner and outer casings and concentric therewith, a driving motor within said inner casing and axially aligned therewith, a rotary gas impeller secured for operation to said driving motor, said impeller consisting of an inner set of radial blades having their inlet side in alignment with the space between said inner casing and said intermediate

10

15

casing, and an outer set of radial blades having their inlet side in alignment with the space between said intermediate casing and said outer casing, said inner set of blades having a greater blade pitch than said outer set of blades, and partitioning duct means adjacent the discharge side of said inner and outer sets of blades for maintaining separate the gas flow through said inner and outer sets of impeller blades.
